THEODORE CLOUGH, OF DOBB'S FERRY, GREENBURG, NEW YORK.

Letters Patent No. 71,281, dated November 26, 1867.

IMPROVEMENT IN LAMPS.

The Schedule referred to in these Letters Patent and making part of the same.

TO ALL WHOM IT MAY CONCERN:

Be it known that I, THEODORE CLOUGH, of Dobb's Ferry, town of Greenburg, in the county of Westchester, State of New York, have invented certain new and useful Improvements in Lamps; and I do hereby declare that the following is a full and correct description thereof, reference being had to the annexed drawings, and to the letters of reference thereon.

My improvements more especially relate to lamps for burning naphtha, gasoline, and other similar light hydrocarbon inflammable oils or spirits, but they are, however, applicable to the burning of kerosene and other of the heavier illuminating oils, by properly reducing the length of the wick-tube, and relatively adjusting the other parts of the burner. My chief object, however, is to utilize, for the purposes of burning in lamps without a chimney, the naphtha and gasoline of commerce, which, being produced in the distillation of petroleum for kerosene and other burning oils largely in excess of the demand for them, are only salable at a very low price in the market.

I have discovered that when air under pressure is injected into the middle of the body of the flame of a wick fed with naphtha, gasoline, and other inflammable oils, in the form of fine jets, such as would be projected by air forced through the nozzle of either a bat-wing or a jet-burner for coal gas, that the flame becomes smokeless, intensified, and stiffened, so as to burn without a chimney, in the manner of jets from gas-burners, and also takes the form of a gas-jet or jets, such as would be produced by the emission of illuminating gas from the jet-pipe nozzle if used without the accompanying wick, and with gas instead of compressed air; and I have also discovered that this mode of supplying air under pressure centrally to and within the body of the flame of the wick is applicable either to a solid round wick of suitable size or to a tubular wick, the nozzle of the air-jet tube being in each case applied immediately over the wick, above the middle thereof, so as to discharge its jet or jets of air into the middle of the flame from the wick.

My said invention consists, first, in combining with the wick-tube of a lamp, suitable for burning hydrocarbon oils and other suitable inflammable oils, a jet-pipe, having its discharging nozzle perforated with fine holes, or by a fine slit, similar to the perforations or slits in gas-burners, when the discharging orifices are placed so that they are or may be brought directly over the middle of the wick, so as to discharge air in the middle of the flame.

Although I can apply the first part of my invention to lamps burning either a solid wick or a tubular wick, I prefer to use the latter, because it enables me to carry the air-jet pipe from within the lamp-reservoir up through the wick and wick-tube in the middle thereof, and to take the supply of air for the jet-pipe from a body of air forced into the upper part of the lamp-reservoir, above the inflammable fluid therein which supplies the wick—a mode of supplying air in a lamp to a different sort of air-jet apparatus that I have described in a prior pending application for Letters Patent of the United States. This mode of supplying air to the jet-pipe keeps the top of the lamp cool, and prevents vapors or gases from forming, or carries them away immediately from the reservoir as they are formed, by reason of the heat of the wick-tube or other causes; and this part of my invention consists in combining with a wick-tube a centrally-placed air-jet tube, the nozzle, with its discharging aperture, being just above the wick, and the pipe leading down through the wick-tube and opening into the upper part of the lamp-reservoir, when said reservoir is provided with a pipe or other suitable means of admitting a constant stream of air, under pressure, into the upper part thereof. Also, in combination with the air-jet pipe, wick-tube, and lamp-cap, an adjusting-screw, whereby the relative adjustment of the jet-pipe and flame may be effected.

And my invention further consists in the employment of a short cylindrical tubular wick in the upper part of the wick-tube, joining the stationary wick in the lower part of the wick-tube. The short section of wick is a great convenience in trimming and cleaning the burner. Being removable, it can be readily lifted out to be cleaned and trimmed, to clean the burner generally, or to be replaced, without disturbing the rest of the wick, which is a permanent, stationary, feeding-wick.

But in order to describe my invention more particularly, I will refer to the drawings by letters of reference.

Figure 1 of the drawings is an elevation of a lamp with my improvements, adapted to table use, shown about half size.

Figure 2, sectional elevation of reservoir and burner of my improved lamp as adapted to tubular wicks.
 Figure 3, sectional elevation, showing application of the air-jet to the middle of a solid wick.

Figures 4 and 5, detached views, plan, and elevation of perforated nozzles for air-jet tube.

In the drawing, fig. 3, there is represented in section the upper part of a lamp-reservoir, *a*, surmounted by a screw-cap, *b*, which holds the wick-tube *c*, containing a round wick, *d*. A sliding-tube, *e*, surrounds the wick-tube, and serves to regulate the extent of the wick ignition by sliding it up and down, as the case may be. A standard, *f*, which rises from the lamp-cap, supports, by an adjustable holder, *f'*, a small pipe, *g*, which may be connected at the outer end *g'* with any suitable reservoir, or means of supplying air under pressure. The end of the pipe, which projects over the wick, is sealed hermetically, and a discharge aperture, *h*, similar to the slit of a bat-wing burner, is made across the upper side of the pipe, just over the middle of the wick. This form of construction gives a flame like that shown in fig. 1; but, as I have before said, I prefer to construct my improvement in a form suitable for tubular wick, as shown in figs. Nos. 1 and 2. In those figures there is represented a reservoir, *a*, surmounted by a screw-cap, *b*, which holds a wick-tube, *c*, containing a tubular wick in two parts, the lower part being stationary in the wick-tube, and the upper part, or short tubular section *d'*, is removable, upwards, for the purpose of trimming, or replacing when partially consumed. This short tubular section may be made by cutting off a section from a long woven tubular wick, or by winding a narrow strip of woven wicking around a mandrel, and securing the outer flap by sewing or tying with a thread. A sliding regulating tube, *e*, surrounds the wick-tube, as usual, to regulate the extent of the wick ignition. The air-jet tube *g* is supported in the central part of the wick-tube by the bracket *i* and adjusting-screw *j*. The upper end of the air-jet tube rises a little above the wick, and terminates in a bulb or nozzle, in which is cut a fine slit, *h*, like the slit in a bat-wing gas-burner. The position of the discharge aperture *h* relatively to the wick is regulated by the adjusting-screw *j*. This form of air-jet under pressure gives a flame similar to that of a gas flame from a bat-wing burner. If it is desired to have the flame of the lamp take the form of radial jets, a finely-perforated nozzle, like that shown in figs. 4 and 5, may be used. The lower end *g'* of the wick-tube is open, so as to receive air under pressure from the upper part of the lamp-reservoir, the wick, which is tubular within the wick-tube, being either flat or bifurcated below the lamp-cap, to allow free communication between the air-jet tube and the reservoir. The inflammable fluid which supplies the wick is placed in the reservoir, filling the same up to the dotted line *a'*, the space above being necessary for the air. If desired, a filling-tube may be placed at the side of the reservoir, surmounted by the usual screw-cap, in such position that the lamp cannot be filled through it above the dotted line. The pressure of the air I use is about the ordinary pressure at which illuminating gas burns steadily. Air under pressure may be admitted by a pipe entering the reservoir in any manner, and discharging into the upper part of the same near the lamp-cap, but I prefer the way shown in the drawings. The air-supply pipe *k* enters the reservoir through the neck *m*, at the bottom of the reservoir, a tubular plug, *n*, being soldered in the neck to hold the pipe *k*, and prevent leakage of the inflammable liquid. A coupling stop-stock, *p*, serves to unite the lamp-reservoir to a hollow stand, *q*, through which a pipe, *r*, passes, and is connected with the stop-cock in the same manner as in table gas-burner stands, and also may be connected at the base of the stand, by a flexible or other connecting pipe, with a reservoir of air under pressure, in the manner that table-stand gas-burners are connected with a source of supply of gas under pressure.

I do not wish to be understood as claiming broadly the application of air under pressure to the flame of a wick to produce an intense flame, or for illuminating purposes; that has been done before my invention by substantially different means. In a former application I have described jets of air, under pressure, impinging upon a lamp-frame laterally from a point or points outside the flame, and impelled air has been applied to a flame within a surrounding cap-deflector like the deflector of an ordinary kerosene flat-wick lamp.

I claim as my invention and improvement in lamps—

1. The combination of an air-jet pipe with the wick-tube of a lamp, when the air-jet pipe is so constructed and arranged as to be capable of discharging air under pressure, in a fine jet or jets, in the middle of the flame of the wick, just above the wick, substantially as described.
2. The arrangement of the air-jet pipe within the wick-tube and lamp-reservoir, when the reservoir is provided with a supply-pipe, by which air is admitted to the upper part of the same, substantially as described.
3. In combination with the air-jet pipe and wick-tube, an adjusting-screw or its equivalent, whereby the position of the discharge-aperture of the air-jet pipe relatively to the wick and wick-tube may be determined.
4. The short tubular removable wick or section of wick, to be used with the stationary wick, substantially as described.

THEODORE CLOUGH.
